ELECTRIC FAN

Charles E. Jones, Chicago, and Robert H. Crowle, Berwyn, Ill., assignors to Hunter Fan and Ventilating Company, Incorporated, Memphis, Tenn., a corporation of Tennessee

Application May 14, 1951, Serial No. 15,168

Term of patent 14 years

(Cl. D26—7)

To all whom it may concern:

Be it known that we, Charles E. Jones and Robert H. Crowle, citizens of the United States, residing at Chicago and Berwyn, respectively, in the county of Cook and State of Illinois, have invented a new, original, and ornamental Design for an Electric Fan, of which the following is a specification, reference being had to the accompanying drawings, forming a part hereof.

In the drawing:

Fig. 1 is a view, in perspective, of an electric fan showing our new design;

Fig. 2 is a front view, in elevation, of the electric fan;

Fig. 3 is a side view, in elevation, of the electric fan; and

Fig. 4 is a rear view, in elevation, of the electric fan.

The characteristic features of our design reside in the portions shown by means of full lines in the drawing.

We claim:

The ornamental design for an electric fan, substantially as shown and described.

CHARLES E. JONES.
ROBERT H. CROWLE.
